UNITED STATES PATENT OFFICE.

JAMES SIME SCOTT, OF BRANTFORD, CANADA, ASSIGNOR OF ONE-THIRD
TO WILLIAM JOHN AIKENS, OF BRANTFORD, ONTARIO, CANADA.

HOT-WATER COOLER.

SPECIFICATION forming part of Letters Patent No. 756,061, dated March 29, 1904.

Application filed July 31, 1903. Serial No. 167,681. (No model.)

To all whom it may concern:

Be it known that I, JAMES SIME SCOTT, a subject of the King of Great Britain, and a resident of Brantford, in the Province of Ontario and Dominion of Canada, have invented 5 a new and Improved Hot-Water Cooler, of which the following is a full, clear, and exact description.

The object of the invention is to provide a 10 new and improved hot-water cooler, more especially designed for use in connection with the water-jacket of an explosive-engine or the like and arranged to insure a quick cooling of the water to keep the cylinder cool at an 15 approximately uniform temperature.

The invention consists of novel features and parts and combinations of the same, as will be more fully described hereinafter and then pointed out in the claims.

20 A practical embodiment of the invention is represented in the accompanying drawings, forming a part of this specification, in which similar characters of reference indicate corresponding parts in all the views.

25 Figure 1 is a side elevation of the improvement as applied. Fig. 2 is an enlarged sectional side elevation of the improvement; and Fig. 3 is a plan view of the same, parts being broken out.

30 The improved hot-water cooler A is preferably arranged in the upper portion of a water-tank B, connected at its lower end by a pipe C with a pump D for forcing the water through the water-jacket of the cylinder of 35 an engine E or other device, the said water-jacket having its outlet-pipe F connected with the cooler A, so that the hot water passing from the water-jacket by way of the pipe F through the cooler A is cooled and collected 40 in the tank B for reuse.

The cooler A is provided with a casing G, having a transverse partition G' extending from the forward end of the casing to within a short distance of the rear end thereof, as 45 plainly shown in Figs. 2 and 3, and from the rear end of this partition G' extends forwardly and upwardly a perforated plate H, leading to the bottom I of an inlet-chamber J, into which the hot water is discharged by the

pipe F. The end of the bottom I adjacent to 50 the perforated plate H is curved upwardly, as at I', and a downwardly-curved plate I² is secured to the top of the casing G and extends into the water-inlet chamber J, as plainly shown in Fig. 2, so that the said 55 curved portions I' and I² form a trap to discharge the water from the inlet-chamber J into a mixing-chamber K, formed in the casing G between the top thereof and the perforated plate H. The perforated plate H also 60 forms, with the partition G', an air-inlet chamber L, connected at its outer end by a pipe N' with a blower N of any approved construction, so that air under pressure is forced through the pipe N' into the air-chamber L, from 65 which the air passes through the perforations in the plate H to mix with the water flowing into the chamber K by way of the trap between the chambers K and J.

The water and air from the chamber K flow 70 around the curved outer end G³ of the casing G into a chamber P, arranged above the bottom G² of the casing G, the top of the chamber P being formed by a perforated plate O, which extends from the inner end of the partition G' to the bottom G² near the outer end thereof, as plainly indicated in Fig. 2. The perforated plate O forms, with the partition 75 G', a water-discharge chamber Q, having an outlet Q' for discharging the cooled water and 80 the air back into the tank B.

The water and air flowing around the end G³ of the casing and through the perforations in the plate O are divided or sprayed, so that by mixing the water with the air in the chamber K and spraying the water and the air into the discharge-chamber Q the water is thoroughly cooled and passes in this condition, with the air, through the outlet Q' into the tank in which the water accumulates, while 90 the air readily escapes from the upper open end of the tank.

The device is very simple and durable in construction and can be readily applied to insure a rapid cooling of the hot water, so as to 95 allow reuse of the water for cooling purposes in the water-jacket of an explosive-engine or other machine on which the device is used.

A suitable purging compound may be placed in the water in the tank B, so as to prevent the formation of scales in the water-jacket of the engine.

5 Having thus described my invention, I claim as new and desire to secure by Letters Patent—

1. A hot-water cooler comprising a mixing-chamber, a water-supply chamber connected with the hot-water supply and provided with 10 a trap discharging the water into the said mixing-chamber, an air-supply chamber connected with an air-supply and located below and separated from the said mixing-chamber by a perforated partition, and a spraying-chamber connected with the mixing-chamber and having a perforated top plate for dividing or spraying the water and air, as set forth.

2. A hot-water cooler comprising a mixing-chamber, a water-supply chamber connected 20 with the hot-water supply and provided with a trap discharging the water into the said mixing-chamber, an air-supply chamber connected with an air-supply and located below and separated from the said mixing-chamber

25 by a perforated partition, a spraying-chamber connected with the mixing-chamber and having a perforated top plate for dividing or spraying the water and air, and an outlet-chamber, into which passes the sprayed air 30 and water, the outlet having a discharge, as set forth.

3. A hot-water cooler comprising a casing having a transverse partition extending from the outer end of the casing to within a short 35 distance of the inner end thereof, perforated plates on opposite sides of the said partition, extending from the inner end thereof outwardly, the one to form a mixing-chamber and an air-chamber and the other to form a spraying-chamber, a discharge-chamber within the 40 said casing, and a water-inlet chamber connected with a water-supply, for discharging the water into the said mixing-chamber, as set forth.

45 4. A hot-water cooler comprising a casing having a transverse partition extending from the outer end of the casing to within a short distance of the inner end thereof, perforated plates on opposite sides of the said partition, 50 extending from the inner end thereof outwardly, the one to form a mixing-chamber and an air-chamber and the other to form a spraying-chamber, a discharge-chamber within the said casing, a water-inlet chamber connected 55 with a water-supply, for discharging the water into the said mixing-chamber, and a trap be-

tween the said water-inlet chamber and the mixing-chamber, the trap being formed by plates, curved in opposite directions and spaced apart, as set forth.

5. In a hot-water cooler, a casing inclosing a mixing-chamber, an air-inlet chamber, a spraying-chamber, and an outlet-chamber, the spraying-chamber being an extension of the mixing-chamber, the mixing-chamber being 65 separated from the air-inlet chamber by a perforated partition and the spraying-chamber being separated from the outlet-chamber by a similar partition, means for simultaneously forcing a current of air and water together 70 into said mixing-chamber to mix the two together, and thence when mixed, forcing the same on through the intervening perforated wall into the spraying-chamber, and an outlet 75 for said spraying-chamber.

6. In a hot-water cooler, a casing inclosing a mixing-chamber, a water-inlet chamber leading into said mixing-chamber, a spraying-chamber forming a continuation of said mixing-chamber, an air-inlet chamber leading into 80 the mixing-chamber between said water-inlet chamber and said spraying-chamber, means for forcing the water into said mixing-chamber and thence into said spraying-chamber, means for forcing air into the mixing-chamber simultaneously with the water to mix the two and thence, when thus mixed, through 85 said spraying-chamber onward into said outlet-chamber, and an outlet for said last-named chamber.

7. A hot-water cooler comprising a casing having a transverse partition extending from the outer end of the casing to within a short distance of the inner end thereof, perforated plates on opposite sides of the said partition, 90 the upper one of which plates extends outwardly and upwardly, and the lower one of which extends outwardly and downwardly, the upper plate forming, with the casing, a mixing-chamber at its top side, and forming with the central plate an air-inlet chamber at its under side, the lower one of said plates forming, 95 with the casing, a spraying-chamber at its under side, and with the central plate, an outlet-chamber at its upper side.

In testimony whereof I have signed my name to this specification in the presence of two subscribing witnesses.

JAMES SIME SCOTT.
